US0D1019589S

(12) **United States Design Patent** (10) **Patent No.:** **US D1,019,589 S**
(45) **Date of Patent:** **** Mar. 26, 2024**

(54) **ELECTRONIC DEVICE**

- (71) Applicant: **Samsung Electronics Co., Ltd.**, Suwon-si (KR)
- (72) Inventors: **Seung-Ho Jang**, Suwon-si (KR); **Da-Wi Lee**, Suwon-si (KR); **Jong-Bo Jung**, Suwon-si (KR); **Mi-Ri Lee**, Suwon-si (KR)
- (73) Assignee: **Samsung Electronics Co., Ltd.**, Suwon-si (KR)
- (**) Term: **15 Years**
- (21) Appl. No.: **29/844,815**
- (22) Filed: **Jul. 1, 2022**

Related U.S. Application Data

- (62) Division of application No. 29/770,218, filed on Feb. 10, 2021, now Pat. No. Des. 966,249.

(57) **CLAIM**

We claim the ornamental design for an electronic device, as shown and described.

DESCRIPTION

FIG. 1 is a rear perspective view of an electronic device showing our new design in accordance with a first embodiment;

FIG. 2 is a rear view thereof;

FIG. 3 is a front view thereof;

FIG. 4 is a left-side view thereof;

FIG. 5 is a right-side view thereof;

FIG. 6 is a top view thereof;

FIG. 7 is a bottom view thereof;

FIG. 8 is a front perspective view thereof;

FIG. 9 is a rear perspective view of an electronic device showing our new design in accordance with a second embodiment;

FIG. 10 is a rear view thereof;

FIG. 11 is a front view thereof;

FIG. 12 is a left-side view thereof;

FIG. 13 is a right-side view thereof;

FIG. 14 is a top view thereof;

FIG. 15 is a bottom view thereof; and,

FIG. 16 is a front perspective view thereof.

(Continued)

The evenly-dashed broken lines in the figures depict portions of the electronic device which form no part of the claimed design.

The pair of closely spaced dot-dash waved lines in the figures indicate the appearance of any portion of the article between the break lines forms no part of the claimed design.

1 Claim, 16 Drawing Sheets
